CIRCUIT CONTROLLER

William Lawrence Butler, Schenectady, and
George M. Hausler, Ballston Lake, N. Y., as-
signors to General Electric Company, a corpo-
ration of New York

Original application June 18, 1941, Serial No.
398,608. Divided and this application Novem-
ber 28, 1942, Serial No. 467,206

8 Claims. (Cl. 200—153)

Our invention relates to circuit controllers, and particularly to means for minimizing or preventing vibration of circuit controller contacts. This application is a division of our copending application Serial No. 398,608, filed June 18, 1941, now Patent 2,310,730.

It is one object of our invention, generally stated, to provide an electric circuit controller which shall have improved efficiency of operation and which shall be inexpensive and easy to manufacture in large quantities.

More specifically, it is an object of our invention to provide means for minimizing vibration and chattering of cantilever spring electric contact elements.

It is a still further object of our invention to provide new and novel adjustment means for cantilever spring contact elements.

By way of illustration we have chosen to show our invention applied to a multipoint electromagnetic motor starter of the type disclosed in Patent No. 2,223,278 issued on November 26, 1940, to Fred H. Winter. The motor starter disclosed in the Winter patent comprises a contactor having a plurality of armatures which are arranged for sequential dropout to control a plurality of normally closed resistance shunting switches. The armatures cooperate with magnetically independent cores which are arranged for simultaneous energization by a single actuating coil. The starter also includes certain interlock switches which have a particular utility in connection with systems similar to those disclosed in the patent. According to the invention the resistance shunting switches are carried by light cantilever leaf springs which are adjustably attached to a contact carrying head portion of the controller mounted adjacent the electromagnet armatures. A second and relatively heavy cantilever spring is mounted in conjunction with each light contact carrying spring to overlie the light spring in parallel engaging relation therewith for the purpose of restraining vibration of the contacts. The heavier cantilever spring is fixedly connected to the fixed end of the light spring and is connected at its free end through a lost motion connection to the free end of the light cantilever spring. Both springs are biased in a circuit closing direction, so that when in the closed position the heavy spring lies against the light spring to prevent chattering of the contacts.

Our invention itself will be more fully understood and its objects and advantages adequately appreciated by referring now to the following

detailed description taken in conjunction with the accompanying drawing, in which Fig. 1 is a side elevation, partly in section, of our circuit controller showing the armatures in their normal deenergized positions; Fig. 2 is an end view of the controller with the parts in the same positions as in Fig. 1; Fig. 3 is a plan view of the controller showing particularly the interlock switch assembly on the controller head; Fig. 4 is a fragmentary view similar to Fig. 1 showing the movable parts of the controller in their actuated positions; and Fig. 5 is an enlarged perspective view of an armature hinge construction, preferably forming part of our circuit controller.

15 Referring now to the drawing, our circuit controller in one form comprises a frame including a base plate 10 upon which are mounted three U-shaped magnetic cores 11, 12, and 13 and four perpendicular mounting studs 14, 15, 16, and 17 20 and a contact head assembly generally designated by the numeral 18 supported upon the studs 14, 15, 16, and 17. The three U-shaped cores 11, 12, and 13 are disposed in alignment with their side legs extending perpendicularly 25 from the base 10 to facilitate the mounting of a common actuating coil upon the forward legs of all the cores.

As best shown at Figs. 1 and 4, each of the 30 U-shaped cores is provided with a magnetic armature 20 arranged across the end faces of the core legs in transverse abutting relation thereby to bridge the gap between the legs at their outer ends. Since the three electromagnets are of similar construction, only one need be described 35 by way of example. The armature 20 of Fig. 1 is pivotally mounted adjacent the end face of the rear leg of the core 11 and biased to a normal position in spaced relation to the end face of the forward core leg by means of a resilient 40 hinge member 21. Referring now particularly to Fig. 5, it will be observed that the resilient hinge member 21 is channel-shaped in cross-section and is stamped to provide a pair of connected bowed spring fingers 25 and 26 extending upwardly from the lower end of the hinge. Adjacent the armature 20 the hinge member 21 is bent inwardly to provide a shoulder 27 positioned to engage the outside of the back leg of the core 11. Preferably the hinge 45 member 21 is placed against an end surface of the armature 20 in a plane perpendicular to the sides of the armature and is fastened to the armature in this position by any suitable means such as welding at 28. Adjacent its upper end 50 face the rear leg of the core member is pro-

vided with a generally T-shaped projection 29 forming upon its side nearest the base 40 a transverse notch 30 adapted to receive the free ends of the spring fingers 25 and 26. The notch 30 is preferably slightly offset laterally from the leg of the core 11, as is best shown at Fig. 5. The other side of the T-shaped projection 29 forms with the rear leg of the core 11 a transverse groove 31 within which the shoulder 27 is seated in the assembled position. As may now be seen by examination of Figs. 1 and 4, the rear face of the armature 20 slightly overhangs the rear leg of the core 11 due to the presence of the inwardly turned shoulder 27. Because of this slight overhang the longitudinally extending hinge 21 lies in parallel spaced relation to the rear leg of the core when the armature 20 is in its attracted position. The dropout movement of the armature 20 is limited by engagement of the lower end of the hinge 21 with the core leg.

In operation the armature 20 pivots about the knife edge formed by the inwardly projecting shoulder 27 in moving from its deenergized position in Fig. 1 to its attracted position in Fig. 4. In pivoting about the knife edge 27 to the position of Fig. 4 the lower end of the hinge member 21 moves through an arc which brings it closer to the notch 30 against the bias of the spring fingers 25 and 26. The tendency of the spring fingers 25 and 26 to assume a straight position normally forces the lower end of the hinge member 21 to the position shown in Fig. 1 and thus biases the armature 20 to its deenergized position spaced from the front leg of the core 11.

The movable ends of the armatures 20 are arranged to engage the end faces of the front legs of the cores 11, 12, and 13 in their actuated positions. Since it is essential to the operation of this device that the dropout voltage of each of the armatures be accurately predetermined, it is necessary to provide means for preventing the armatures from sticking to their associated cores due to the residual magnetism of the cores. For this purpose we have shown shims 32 of suitable nonmagnetic material fastened to the lower sides of the armatures 20 in the region of their engagement with the cores 11, 12, and 13.

To provide for operating the various motor controlling and interlock contacts associated with our circuit controller, the movable end of the armature 20 has attached thereto a block of insulating material 33 formed to provide a contact operating pin 34 and a damping buffer 35.

The contact carrying controller head 18 comprises a flat base 40 formed of a molded insulating compound and mounted upon the outer ends of the studs 14, 15, 16, and 17. The base 40 has mounted upon the inner side thereof a plurality of movable motor controlling contacts 41 and carries upon its outer surface a number of interlock contacts which preferably are connected in circuit as shown in the above-mentioned Winter Patent No. 2,223,278 and will be described in greater detail hereinafter. As best shown at Figs. 1 and 4, each of the movable motor controlling contacts 41 is mounted upon the free end of a relatively light cantilever spring 42 which is biased toward the base 40 to hold the contacts 41 in engagement with cooperating fixed contact strips 43 mounted upon the inner side of the insulating base 40. Each of the fixed contact strips 43 is formed to provide at the opposite end thereof a terminal conductor extending beyond the insulating base 40.

Each cantilever spring 42 is connected in spaced relation to the inner side of the base 40 by means of a bolt 45 extending through the base 40 and threaded into a plate 46 below the spring. The contact carrying cantilever springs 42 are thin and of relatively small mass so that their inertia and hence their tendency to rebound after engaging the stationary contacts 43 are minimized. To further assist in preventing rebound of the movable contacts 41 and to increase the contact pressure when the contacts are in their normal closed positions, a second relatively heavy cantilever spring 47 is also mounted upon each bolt 45 adjacent and parallel to the spring 42. As shown in Winter Patent No. 2,223,278, all the movable contacts of this type of circuit controller are connected together to a common external terminal. In our improved controller this connection is effected and the cantilever springs 42 and 47 are spaced from the base 40 by a T-shaped contact plate 48 which extends across the rear side of the base 40 and is pierced by each of the spring securing bolts 45 (Fig. 3). The contact plate 48 also extends beyond the rear side of the base 40 to provide a common external terminal connector. The heavy springs 47 are biased toward the base 40 and into engagement with the relatively light springs 42 along substantially their entire length.

To provide for operative connection of the contacts 41 to the movable ends of the armatures 20, the relatively heavy springs 47 are slit and bent toward the armatures to form slotted hangers 49 to receive the pins 34 and to leave central forwardly extending pins 50. The free ends of the light cantilever springs 42 are similarly slotted and bent toward the armatures in parallel spaced relation to the hangers 49 to form hooks 55 for engaging the pins 50. Since the springs 47 are biased toward the controller head 18, the hangers 49 assist the spring hinges 21 in moving the armatures to their deenergized positions.

In order to insure a constant preadjusted minimum pressure at the contacts 41, 43 the cantilever springs 42 and 47 are provided with an adjusting bolt 60 which passes through the insulating base 40 slightly forward of the spacer 48 and is threaded into the plate 46 to draw the cantilever springs 42 and 47 toward the base 40. Each bolt 60 comprises a lower externally threaded shank portion extending from the bottom of the base 40 and a cylindrical head 61 positioned with a cylindrical recess 61a in the base 40 and seated upon a shoulder formed at the bottom of the recess.

To provide for application of additional tension to the cantilever springs whereby the separate armature 20 may be independently adjusted to drop out in sequential timed relation as the energization of the actuating coil 19 decays, the cylindrical bolt heads 61 are threaded longitudinally to receive second adjusting bolts 62. The heads of the bolts 62 are seated upon removable plates or washers 63 which rest upon shoulders formed by the top of the recesses 61a thereby to raise the entire bolts 60 from the shoulders at the bottom of the recesses.

Thus by removing the bolts 62 and the plates 63 access may be obtained to the lower bolts 60. Each of the motor controlling contacts 41 may be adjusted for a predetermined minimum constant contact pressure by adjusting the lower bolt 60 with the upper bolt 62 and the plate 63 removed. When the desired minimum contact pressure is obtained the permanence of the adjustments is

preferably assured by soldering the lower bolt 60 to the threaded plate 46 as indicated at 64. With the minimum contact pressure adjustment completed for each of the motor controlling contacts, the plate 63 and the bolts 62 may be replaced. The bolts 62 may now be adjusted to determine the dropout voltages of the various armatures thereby to provide a timing adjustment for the various motor controlling contacts to insure the desired sequential closure of the contacts as the energization of the coil 19 decays. If desired the permanence of the timing adjustment when obtained may be insured by soldering the bolts 62 to the nonrotatably seated plates 63.

Mounted on the outer surface of the insulating base 46, we have shown a pair of interlock contacts 65 and 66 carried at opposite ends of a strip 67 of electrically conducting material. The interlock contacts 65 and 66 may of course be used in any desired circuit relation, but when our circuit controller is used in connection with the motor controlling system of Winter Patent No. 2,223,278 we prefer to connect the contacts 65 and 66 in series in a manner similar to the interlock contacts 29a and 29b of the patent. The conducting strip 67 is slotted and slidably mounted upon a pair of studs 68 and 69 projecting from the base 46. To bias the contact strip 67 toward the base 46 and into contact engaging position, a pair of compression springs 70, 71 is mounted between the strip 67 and a pair of stops 72, 73 upon the studs 68, 69, respectively. As shown in Figs. 1 and 2, when the three armatures 20 are in their deenergized positions the contact strip 67 is forced to contact disengaging position against the bias of the springs 70 and 71 by a plurality of slidable pusher rods 75, 76, and 77. Each of the rods 75, 76, and 77 passes through the insulating base 46 and engages one of the relatively stiff contact springs 47. The upper ends of the pusher rods 75, 76, and 77 are provided with shoulders engaging the under side of the contact strip 67 and with extending tongue portions passing through the contact strip.

The extending tongue portions of the pusher rods are provided on all the rods only for the purpose of uniformity, since in our preferred form of contactor only one of these extending tongue portions is used. It will be understood, however, that if desired additional interlock switches may be added in connection with the extending tongues of the other pusher rods. By way of example we have shown a normally closed interlock contact 80 connected to one end of a pivoted lever 81, the other end of which engages the extending tongue of the pusher rod 77. The lever 81 is pivoted to a projecting stud 82 mounted upon the base 46 and is biased to contact opening position by a compression spring 83. However, with the circuit controller in its deenergized condition the pusher rod 77 is raised and holds the interlock contact 80 in its closed position. When our circuit controller is used in the system disclosed in the above-mentioned Winter patent we prefer to connect the interlock contact 80 in a manner similar to the interlock contact 26 of the patent.

In operation, when the actuating coil 19 is energized, the three cores 11, 12, and 13 are simultaneously magnetized and the three armatures 20 are simultaneously drawn to their attracted positions. As each armature 20 begins to move toward its attracted position it draws with it the relatively heavy spring 47. After a certain amount of lost motion the forwardly extending pin 50 on the free end of the spring 47 engages

the hook 55 on the relatively light spring 62 and draws the spring 47 away from the base 46 to open the motor controlling contacts 41, 43. As the armatures 20 move toward their attracted positions the consequent movement of the free ends of the springs 47 permits the springs 70 and 71 to depress the contact strip 67 and the pusher rods 75, 76, and 77, thereby to close the contacts 65 and 66. This movement of the pusher rod 77 also permits the spring 83 to rotate the lever 81 in a clockwise direction, as viewed in Fig. 1 to open the interlock contact 80 as at Fig. 4.

As shown in the Winter patent, release of a manually operated "start" switch removes the actuating coil from the line and permits the charge of a timing condenser gradually to decay through the coil 19. As the energization of the coil diminishes, the armatures 20 are released in sequential time relation as determined by the thickness of the shims 32 and by the adjustment of the various bolts 62 previously described. As each armature 20 is released, it moves away from the core 11 along with both of the springs 47 and 47. When the contact 41 engages the fixed contact 43, the relatively light spring 47 ceases its movement, and the heavy spring 47 and the armature 20 continue to move to take up the lost motion. As has been previously pointed out, the inertia of the relatively light spring 47 is so small that no appreciable rebound of the contact occurs upon its initial engagement. As the heavy spring 47 continues to take up the lost motion after engagement of the contacts 41 and 43, it gradually engages the light spring 62 along an ever increasing length thereby gradually to increase the contact pressure and to assist in preventing rebound of the contact 41. The armature 20 follows the heavy cantilever spring 47 so that the buffer 36 of the armature, which is closely adjacent the spring 47, tends to prevent oscillation of the heavy spring.

Regardless of which of the armatures 20 is first released, the release of the first armature raises the associated pusher rod to open either the contact 65 or the contact 66 and thus break the series interlock circuit through these contacts. If our circuit controller is used in either of the control systems disclosed in the Winter patent, the last armature to be released is that associated with the core 13 and the pusher rod 77. When this last armature is released the pusher rod 77 engages the lever 81 and rotates it in a counterclockwise direction, as viewed in Fig. 1, thereby to reclose the interlock contact 80.

While we have shown but one preferred embodiment of our invention by way of illustration, many modifications will occur to those skilled in the art, and we therefore wish to have it understood that we intend by the appended claims to cover all such modifications as fall within the true spirit and scope of our invention.

What we claim as new and desire to secure by Letters Patent of the United States, is:

1. A circuit controller comprising a base, a fixed contact mounted upon said base, a pair of cantilever springs mounted upon said base in parallel engaging relation, one of said springs having a mass substantially less than that of the other of said springs and carrying at its free end a movable contact, said light spring being biased to maintain said movable contact in engagement with said fixed contact, the other of said springs overlying said light spring and being biased to hold said light spring in a contact gap.

gaging position, lost motion connecting means between the free ends of said springs, and means engaging the spring of greatest mass for moving both said springs against their bias to a contact disengaging position.

2. An electric circuit controller comprising a base, a fixed contact mounted upon said base, a relatively light cantilever spring connected to said base and carrying at its free end a movable contact arranged for cooperation with said fixed contact, said spring biasing said movable contact into contact engaging position, a second cantilever spring fastened to said base and extending in substantially parallel engaging relation to said first spring overlying said first spring and, said second spring being biased to hold said first spring in a contact engaging position, a lost motion connection between the free ends of said springs whereby said second spring loosely engages said first spring to open said contacts, and actuating means connected to said second spring to move both said springs to a contact disengaging position.

3. An electric circuit controller comprising a base, relatively light and relatively heavy cantilever springs mounted upon said base in parallel engaging relation, a movable contact mounted upon the free end of said light spring for cooperation with a fixed contact mounted upon said base, said light spring being biased to maintain said contacts in engaging position and said heavy spring overlying said light spring and being biased to a position of parallel engagement, the free end of said light spring being formed to provide a slotted projection extending toward and loosely engaging said heavy spring, said heavy spring being formed to provide a second slotted projection, and an actuating pin arranged to engage said second slotted projection for moving both said springs against their bias to a contact disengaging position.

4. An electric circuit controller comprising a base of insulating material, a fixed contact mounted upon the one side of said base, a relatively light cantilever spring carrying at its free end a movable contact for cooperation with said fixed contact and mounted upon said one side of said base, the free end of said spring being slotted and bent away from said base to provide a hook, a relatively heavy cantilever spring overlying said light cantilever spring in parallel engaging relation therewith, common means for connecting said springs to said base, both said springs being biased to maintain said contacts in engaging position, the free end of said heavy spring being slotted and bent away from said bases to provide a hanger and an extending pin, said pin being arranged for loose engagement with said hook, and an actuating pin of insulating material arranged to engage said hanger to move both said springs against their bias, thereby to disengage said contacts.

5. An electric circuit controller comprising a base, cooperating switch contacts, a cantilever spring for controlling one of said contacts, means for connecting one end of said spring in spaced

relation to said base, an adjusting bolt engaging said spring intermediate its ends to draw the free end of said spring toward said base, said bolt having a head seated upon a shoulder formed upon said base, and means for adjustably raising said head from said shoulder thereby further to draw said spring toward said base.

6. An electric circuit controller comprising a base, cooperating switch contacts, a cantilever spring for controlling one of said contacts, connecting means for fastening one end of said spring to said base, spacing means between said base and said one end of said spring, a first adjusting bolt engaging said spring adjacent said spacing means to draw the free end of said spring against said base with a predetermined minimum pressure, said first bolt having an internally threaded cylindrical head seated upon a shoulder formed upon said base, and a second adjusting bolt threaded into said head and seated upon a second shoulder formed upon said base thereby adjustably to increase said pressure.

7. An electric circuit controller comprising a base of molded insulating material, a fixed contact secured to said base, a cantilever spring carrying at its free end a movable contact, spacing means between the fixed end of said spring and said base, connecting means for fastening said fixed end of said spring to said base, a first adjusting bolt engaging said spring adjacent said spacing means to draw said contacts into engagement with a predetermined minimum pressure, said first bolt having a cylindrical head portion seated upon a shoulder formed at the bottom of a recess in said base, said cylindrical head being internally threaded in alignment with said first bolt, a second adjusting bolt threadingly engaging said cylindrical head and having a head portion seated upon a second shoulder formed upon said base thereby adjustably to increase said pressure, and actuating means connected to the free end of said spring to open said contacts.

8. An electric circuit controller comprising a base, fixed and movable switch contacts, a relatively light cantilever spring strip having a fixed end mounted upon said base and carrying at its free end said movable contact, said spring being biased to a contact engaging position, a second and relatively heavy cantilever spring strip mounted upon said base in the region of the fixed end of said light spring and overlying said light spring in substantially parallel engaging relation therewith on the side thereof remote from said movable contact, said heavy cantilever spring being biased in the same direction as said light cantilever spring to hold said light spring in contact engaging position thereby to prevent vibration of said movable contact, a lost motion connection between the free ends of said springs, and actuating means for engaging said second spring to separate the free ends of said springs and to move said light spring to a contact disengaging position.

WILLIAM LAWRENCE BUTLER.
GEORGE M. HAUSLER.
